UNITED STATES PATENT OFFICE.

VICTOR ANGERER, OF RIDLEY PARK, PENNSYLVANIA, ASSIGNOR TO WILLIAM WHARTON, JR., & COMPANY, INCORPORATED, OF EASTON, PENNSYLVANIA, A CORPORATION OF PENNSYLVANIA.

SWITCH TONGUE.

Application filed February 27, 1923. Serial No. 621,552.

To all whom it may concern:

Be it known that I, VICTOR ANGERER, a citizen of the United States, residing at Ridley Park, in the county of Delaware and 5 State of Pennsylvania, have invented certain new and useful Improvements in Switch Tongues, of which the following is a specification.

Switch tongues, as ordinarily and heretofore constructed, are of shallow and substantially uniform depth and their seat with respect to the switch body is necessarily interrupted both longitudinally and laterally thus developing potential weaknesses in consequence of which they are susceptible of tilting and are liable to breakage and distortion under modern traffic conditions.

Objects of this invention are to provide a switch tongue possessed of great strength 20 and which under all conditions of service will be firmly seated and will have a flush bearing its entire length and throughout its width in the complementary tongue receiving pocket or bed of the switch body and hence will be immune to tilting, breakage or distortion; to provide a switch tongue whereof the bottom constitutes a continuous or intact longitudinal bearing area for co-operation with a corresponding bearing area 25 in the switch body; to provide a switch tongue whereof the bottom also constitutes a continuous or intact lateral bearing area for co-operation with a like bearing area in the switch body; to provide a switch tongue 30 whereof the bottom has an endwise directed slant or taper whereby there is established a relatively shallow point and a relatively deep heel or pivotal portion; to provide a switch tongue whereof the bottom has a continuous longitudinal taper and a continuous lateral taper; to provide a switch tongue of 35 the character stated which, whether solid or otherwise, is of such section as to insure inherent strength through a substantially uniform 40 distribution of metal; to provide appropriate drainage facilities; to provide for co-operation of tongue actuating or locking mechanism without disturbing or interrupting the continuity of the bearing surfaces hereinbefore recited; and to provide a switch body constructed, arranged and adapted to receive and co-operate with a switch tongue 45 of the nature indicated.

With such and other objects in view, the 50 nature, characteristic features and scope of

the invention will more readily be understood from the following description taken in connection with the accompanying drawings, forming a part hereof, wherein—

Figure 1 is a plan view of a switch structure embodying my improvements.

Fig. 2 is a side elevational view of the tongue.

Figs. 3, 4, and 5 represent sections taken, respectively, on lines 3—3, 4—4, and 5—5 of Fig. 2.

Fig. 6 is a longitudinal sectional view of a switch body and tongue, showing the continuous or intact longitudinal taper bearing common to said elements.

Fig. 7 is a transverse section exemplifying drainage facilities.

Fig. 8 is a sectional view of a modification wherein the tongue and its complementary bed or pocket are served with compound taper bearing surfaces, that is to say with a continuous or intact longitudinal taper and with a continuous or intact transversely ranging or lateral taper; the section being taken at the pivotal end of the tongue.

Fig. 9 is another sectional view of the lateral taper, the section being taken near the point of the tongue.

Fig. 10 is a sectional view of a tongue of I beam section.

According to my invention, I provide a switch structure of inherently great strength and possessed of other advantages, as previously remarked, by constructing the tongue and its complementary bed or pocket so that the bottom of the tongue and the floor of the bed will have a continuous or uninterrupted longitudinal bearing established on an inclined plane; that is to say tapered endwise or in other words inclined from the horizontal.

The utility of and the advantages attendant on such construction will at once manifest themselves to those skilled in the art. For example, a tongue formed with a downward slant has the desirable attribute of unusual depth at the heel or pivotal portion and proportional increased depth of body diminishing gradually and ultimately terminating in a relatively thin or shallow point. Such a tongue is infinitely stronger than the ordinary tongue, which, as is well known, is of shallow and uniform depth. The taper construction insures substantial lodgment or firm seating of the tongue be-

cause it admits of intact or flush bearing surfaces and provides ample depth of body to permit the passage therethrough of instrumentalities for holding and tightening the tongue and for actuating it, and hence there is no necessity for the usual depending lugs or other appendages such as interrupt the bearing of the ordinary tongue; the taper construction operates by gravity to maintain close contact at the heel; it insures precision in the operation of the tongue; it facilitates drainage; and modified, as hereinafter specified, it admits of the point being elevated sufficiently to enable it to act as a raised guard. Moreover, the establishment of the bearing in a single uninterrupted plane greatly simplifies planing and hence works a desirable economy in the finishing of the tongue.

20 All of the advantages stated, and others, are achieved with a tongue the bottom plane or surface of which is formed with a continuous or intact taper which may and preferably does include the point and heel; and 25 whether the tongue be constructed of box section or of I beam section, or of any other appropriate section.

Referring to the drawings, the numeral 5 represents the switch body and 6 represents 30 the tongue. The bottom surface 7 of the latter has an endwise directed taper, that is to say it is inclined longitudinally from the horizontal; the maximum depth of the inclined body being at the heel or pivotal portion 35 8, which accordingly is of unusual and considerable depth. The tongue seating bed 9 of the switch body is correspondingly formed and by reason of the inclined plane and the continuous or intact longitudinal bearing area thus established between the 40 tongue and its bed, the tongue is always firmly seated and hence is not free to tilt.

While the switch body and the tongue may be as usual, except as regards that part 45 of the invention which demands the continuous or symmetrical taper in the bottom plane of the tongue, it is a merit of the invention that the switch body externally of the tongue bed may have depending cross 50 ribs 10, the presence of which insures adequate strength with a comparatively light construction of switch body.

In one form of the invention, the tapered or wedge shape tongue for a material portion 55 of its length is of substantially box section, as indicated at 11, with intact top and bottom walls joined by vertical ribs 12 forming the side walls and also forming between them windows 13 of progressively diminishing size as they approach the shallow point. The heel or pivotal portion is also by preference of hollow form, as indicated at 14.

In another form of the invention, Fig. 10, 60 the tongue is of I beam section with a cen-

tral or vertical web 15, a head or tread portion 16, and a base 17. It may be constructed without slots or openings, but the provision of slots or openings in the vertical web, corresponding to those of the box section, is 70 desirable. They are indicated at 18. The heel or pivotal portion is the same or substantially the same as in the box section.

The box section and the I beam section have the common merit that they insure a 75 sturdy and inherently strong structure in that each provides for substantially uniform distribution of metal; and this provision, in the case of a casting, is conducive to uniformity of heat treatment, thus making for 80 further strength. The slot-work or windows have the added utility of by-passing fluid mud, water, and other extraneous matter and thereby tend to ease the operation of the switch. The chamber or receptacle established by the box section is useful to trap and store dirt and other substances which otherwise might militate against proper 85 functioning of the tongue. The taper or wedge form common to both designs is important for the further reason that it offers a simple solution of the problem of securing the tongue with relation to the switch body without resorting to the usual depending lugs. For example, I may employ an element 19 passing through one of the slots or openings in the tongue and engaging the switch body. Manifestly, the hold-down and tightening device 19 is merely illustrative of any means for accomplishing the end 90 sought.

The gradient established by the described type of switch provides for natural drainage towards the pivotal portion thereof and suitable drainage boxes 20, Fig. 7, are provided for the reception of matter passing 95 through the passages 21 in the side walls of the switch body.

Another merit of the invention is the lateral taper hereinbefore alluded to and 100 which, without disturbing the normal tread surface, enables the point of the tongue to rise sufficiently to constitute a raised guard. The lateral taper is indicated at 22, and it will be understood that the bottom of the 105 tongue and the floor of the tongue receiving pocket are inclined from side to side throughout their length. The increased efficiency of the tongue by reason of its intact or continuous lateral taper whereby the 110 point of the tongue is adapted to be elevated the required distance to enable it to act as a raised guard for the wheel when set for the curved track is rendered possible by the establishment in the same plane of the 115 intact or continuous longitudinal taper and by the considerable depth of the heel resulting therefrom. It is apparent that the 120 point may ride the transverse incline without in any way disturbing the normal tread 125

and without interrupting the continuity of its seat on the floor of the tongue pocket.

It will further be noted, that the side walls of the tongue bed or pocket are undercut, as at 23, to conform to the profile of the tongue which is thus enabled to fit flush therewith against and exclude objects which otherwise might wedge themselves between said walls and the tongue.

- 10 Finally, attention is directed to the fact that the described type of switch readily lends itself to the direct application of any form of switch operating mechanism and wholly obviates the necessity of projecting lugs and the like which are essential to shallow tongues. As an example of such direct application, the connection may be effected through the medium of the opening 24 extending transversely of the tongue and opposite a complementary slot or opening in the tongue body.

Having described the nature and objects of the invention, I claim:

1. A switch tongue having a shallow point and a deep heel or pivotal portion and having a continuous or intact bottom bearing area which is inclusive of the heel.
2. A switch tongue having its bottom formed with an endwise directed inclination to provide a deep vertical pivot.
3. A switch tongue having a downward slant continued through a vertical heel.
4. A switch tongue having a shallow point and a deep heel or pivotal portion joined on a common slant.
5. A switch tongue having at one end a shallow point and at the other end a relatively deep heel of substantially cylindrical form, the heel and point having a common bottom bearing.
6. A switch tongue having a shallow point and a deep heel or vertical pivotal portion joined by an uninterrupted bottom bearing, common to the point and heel.
7. A switch tongue terminating at one end in a shallow point and at the other end in a relatively deep heel mainly of cylindrical contour, said heel and point having a common bottom bearing free from surface breaks.
8. A switch tongue of wedge form in side elevation, the maximum depth being at the heel.
9. A switch tongue terminating at one end in a shallow point and at the other end in a relatively deep heel the vertical walls of which are substantially cylindrical, said heel and point having a common bottom bearing formed by a continuous longitudinal taper.
10. A switch tongue having a shallow point and a deep vertical pivot and having its bottom formed with a continuous or uninterrupted longitudinal taper and free from projections to thereby establish a common bearing for the point and pivot.

11. A switch tongue terminating at one end in a shallow point and at the other end in a relatively deep heel the vertical walls of which are substantially cylindrical, said heel and point having a common bottom bearing formed by a taper in which both participate and which is finished in a single plane.

12. A switch tongue terminating at one end in a shallow point and at the other end in a relatively deep heel the vertical walls of which are substantially cylindrical, said heel and point having a common bottom bearing formed by a compound taper finished in a single plane and free from surface breaks.

13. A switch tongue having its bottom inclined from end to end and from side to side.

14. A switch tongue having its bottom formed with a continuous longitudinal taper ranging the length of the tongue, and also formed with a continuous lateral taper.

15. A switch tongue having its bottom inclined from end to end and from side to side, said tongue consisting of a structure whereof the metal is substantially uniformly distributed.

16. A switch body having the floor of its tongue receiving pocket inclined in one plane in the direction of its length.

17. A switch body having the floor of its tongue receiving pocket inclined in the direction of its length, the maximum depth established by the incline being at and in the region of the heel receiving end of the pocket.

18. A switch body having the entire floor of its tongue receiving pocket formed on an inclined plane and presenting a smooth or intact bearing surface for the tongue.

19. A switch body having the floor of its tongue receiving pocket formed with a continuous longitudinally ranging incline finished in a single plane.

20. A switch body whereof the tongue receiving pocket has its full floor portion slanted in one plane to accommodate a tongue having a relatively deep vertical pivot and a shallow point formed with a corresponding common slant.

21. A switch body having the floor of its tongue receiving pocket inclined longitudinally and also laterally.

22. A switch body having the floor of its tongue receiving pocket formed with a continuous longitudinal inclination and with a continuous lateral inclination.

23. A switch body having a tongue receiving pocket of considerable depth at the heel end and of gradually diminishing depth in the direction of the point.

24. A switch body having a tongue receiving pocket of considerable depth at the heel end and of gradually diminishing

depth in the direction of the point, the floor of the pocket presenting a continuous or intact seat for the tongue.

25. A switch body having a tongue receiving pocket the floor of which is finished in a single plane inclined from point to heel.

26. A switch body having a tongue receiving pocket of wedge form in vertical section, the floor of the pocket having a flush surface to seat a tongue the entire under portion of which is finished in a single plane.

27. A switch body having a tongue receiving pocket the floor of which is finished in a single plane inclined from point to heel, whereby drainage is towards the heel end of the pocket, and means for draining the heel end.

28. A switch body having a tongue receiving pocket of wedge form in vertical section and formed by an uninterrupted inclination of the floor from end to end of the pocket to provide for a deep pivotal connection of a tongue having a shallow point.

29. A switch body having a tongue receiving pocket of great depth at the heel end and of gradually diminishing depth towards the point, the variable depth being established by a floor finished in a single plane inclined from the horizontal.

30. A switch body having a tongue receiving pocket the floor of which is inclined from the horizontal both longitudinally and laterally, the lateral inclination being of such nature as to constitute means for elevating the point of the tongue.

31. A switch structure of the type recited, comprising the combination of a switch body having a sloping tongue receiving pocket, and a tongue having its under portion correspondingly sloped, whereby said elements are held by gravity to close contact at the heel end.

32. A switch structure of the type recited, comprising the combination of a switch body having a downwardly slanting tongue receiving pocket, and a tongue of wedge form in vertical section and having its under portion finished in a single plane to have a flush bearing in said pocket.

33. A switch structure of the type recited, comprising the combination of a switch body having a tongue receiving pocket the floor of which has a continuous longitudinal inclination and a continuous lateral inclination, and a tongue having its under portion shaped to fit the floor.

34. A switch structure of the type recited, comprising the combination of a switch body having a downwardly slanting tongue receiving pocket, and a tongue having a co-operating fit in said pocket and whereof the point is adapted to be elevated the re-

quired distance to enable it to function as a raised guard.

35. A switch structure of the type recited, comprising the combination of a switch body having a downwardly slanting tongue receiving pocket, means for draining it, and a tongue having a continuous seat or bearing in the pocket and inclined from side to side and co-operating with a correspondingly formed surface of the pocket whereby the point is adapted to be elevated the required distance to enable it to act as a raised guard.

36. A switch structure having a gradient established on a single plane whereby drainage is towards the heel end thereof, and drainage relief devices co-operating therewith.

37. A switch structure, including a pivotal tongue having a slanted bottom providing an intact or continuous bearing area from end to end thereof, and means ranging transversely of the tongue for the direct application of switch controlling mechanism.

38. A switch tongue of gradually increasing depth in the direction of the pivotal portion, said tongue being of such section as to provide for substantially uniform distribution of metal.

39. A switch tongue having the usual tread and having its bottom inclined on symmetrical lines from end to end to thereby provide a shallow point and a deep heel the common bearing surface whereof is finished in a single plane.

40. A switch tongue having the usual tread surface and having its bottom inclined two ways.

41. A switch tongue having a deep heel the bottom of which is tapered, the taper starting in the region of the point and terminating at the extreme edge of the heel.

42. A switch tongue having a sloping bottom to provide a shallow point and a deep heel or pivotal portion, said bottom being free from projections whereby it presents a single plane for finishing purposes.

43. A switch tongue having a sloping bottom to provide a shallow point and a deep heel or pivotal portion seated on a common plane, said pivotal portion being hollow.

44. A switch tongue having a shallow point and a deep heel or pivotal portion joined on a plane inclined from the horizontal.

45. A switch tongue having a shallow point and a deep heel or pivotal portion joined on a plane inclined in two directions.

46. A switch tongue having a shallow point and a deep heel or pivotal portion joined on a plane continuously inclined in two directions.

47. A switch tongue having a shallow point and a relatively deep heel or pivotal portion joined on a plane that is continu-

ously inclined in two directions, one of the inclinations constituting means for use in elevating the point of the tongue.

48. A switch tongue having a substantially level tread and having a sloping bottom to provide a structure of graduated depth, said structure having cored areas.

49. A switch structure comprising the combination of a switch body having a downwardly slanting tongue receiving pocket, a tongue having its under portion formed to have a flush seat in said pocket, and means for securing the tongue with relation to the body.

15 50. A switch structure, comprising the combination of a switch body having a rearwardly sloping tongue bed, a tongue having its under portion correspondingly formed to fit the bed, and means ranging transversely 20 of the tongue and body for securing them relatively.

25 51. A switch structure, comprising the combination of a switch body having a rearwardly sloping tongue bed, a tongue formed to fit the bed, and means in advance of the pivotal portion of the tongue for securing it with relation to the body.

30 52. A switch structure, comprising the combination of a switch body having a downwardly sloping tongue bed, the maximum depth being at the heel end thereof, a tongue having a mated slope, and means adjacent the heel end for securing the tongue in operative relation with the body.

35 53. A switch structure of the type recited, comprising the combination of a switch body having a downwardly sloping tongue bed, a tongue adapted to said bed and having a transverse opening adjacent its pivotal portion, and means extending through said opening and engaging the switch body for securing the tongue.

40 54. A switch structure of the type recited, comprising the combination of a switch body having a downwardly slanting tongue receiving pocket equipped with drainage provisions, and a tongue adapted to said pocket and having by-passing provisions.

55. A switch structure of the type recited, comprising the combination of a switch body having a tongue receiving pocket, and a tongue seated in said pocket on an inclined plane, said pocket having undercut surfaces to insure close contact of the tongue. 55

56. A switch structure of the type recited, comprising the combination of a switch body having a tongue receiving pocket of graduated depth and whereof the floor is continuously inclined from side to side, and a tongue whereof the under portion is correspondingly formed whereby the lateral incline may be availed of to elevate the point of the tongue.

57. A switch structure of the type recited, comprising the combination of a switch body having a tongue receiving pocket whereof the floor has a continuous longitudinal incline and a continuous lateral incline, and a tongue having its under portion correspondingly inclined whereby in the movement of the tongue the top of its point is raised from the level of the wheel tread to the level of the guard. 70

58. A switch tongue having a shallow point and a vertical pivot of considerable depth formed with a common bottom bearing established on a slant, and means for applying switch actuating mechanism without disturbing said bearing. 75

59. A switch tongue having a shallow point and a vertical pivot, the under portion of the tongue being finished in a single plane inclined from the horizontal to provide common seating means for the point 85 and pivot, the tongue having a transverse opening for the direct application of a switch control.

60. A switch body having a tongue receiving pocket the floor of which is braced and finished in a single plane inclined from the horizontal to accommodate a tongue having a shallow point and a relatively deep vertical pivot. 90

In testimony whereof I affix my signature. 95

VICTOR ANGERER.
